CONTROL DEVICE

Carl G. Kronmiller, Minneapolis, Minn., assignor
to Minneapolis-Honeywell Regulator Company,
Minneapolis, Minn., a corporation of Delaware

Application November 6, 1940, Serial No. 364,525

19 Claims. (Cl. 200—139)

The present invention relates to control devices such as temperature and humidity controls but is more particularly directed to such a device which is both manually adjustable and adjustable by time as determined by a clockwork.

An object of the invention is to provide a thermostat or like device in which means are provided for adjusting the control point according to a timed program.

Another object is to provide a control device in which the usual manual adjustment of the control point is supplemented by means for adjusting the control point according to a timed program.

Further objects will be apparent from the following description, from the claims and from the drawing, in which:

Figure 1 is a view of the front of a thermostat embodying the present invention, and

Figure 2 is a sectional view taken below certain of the parts shown in Figure 1.

It is often desirable in processing various products to control their temperature in a definite relation to the elapsed time from the start of the process. Usually this is accomplished by an attendant who watches a thermometer and manually varies the amount of heating or cooling supplied to the chamber or enclosure which contains the product. The particular thermostat illustrated has been designed to control the temperature in tobacco drying barns.

Briefly the invention as illustrated comprises a base on which a bimetal spiral is adjustably supported. The bimetal in turn carries a mercury switch. An arm is provided for rotating the bimetal in order to select the temperature at which the mercury switch will make and break an electric circuit. A spring run clockwork which is also mounted on the base has a shaft extending therefrom by which it is wound and which it also drives. A cam on this shaft determines the position of a lever adjacent the temperature selecting lever, which lever is provided with a spring latch so that when the clockwork is wound the latch will engage the temperature selecting lever. As the clockwork runs it will raise the temperature setting of the thermostat at a rate depending on the shape of the cam. The time adjustment can be supplanted by manual adjustment at any time by releasing the latch connecting the two levers.

Referring now to the two figures of the drawing the thermostat is mounted on a base 10 and is provided with a cover 11, the top portion of which is shown in Figure 1. A manually adjustable arm 13 is pivoted on a stud 14 which is suit-

ably secured to the base 10. The arm 13 extends beyond the bottom of the base 10 and underneath a temperature indicia plate 16 which is secured in spaced relation to the base 10 by a pair of screws 17. The base 10 is so formed as to hold the plate 16 in spaced relation to the main body of the base in order that the adjusting arm 13 may extend between the base 10 and the plate 16. A flat disc 18 is secured in spaced relation to the adjusting arm 13 at a point adjacent the top edge of the indicia plate 16 to serve as a guide for the arm 13. The outer surface of the disc 18 extends downwardly beyond the upper edge of the plate 16 in such a way that the plate 16 provides a runway for the disc 18 and adjusting arm 13.

The manual adjusting arm 13 has secured thereto an angle member 20 on which is mounted a spiral 22 of thermostatic bimetal. A calibrating adjustment is provided between the angle member 20 and the adjusting arm 13. Angle member 20 is pivoted on the stud 14 on which the adjusting member 13 is pivoted. Member 20 is also provided with a slot 23 through which a screw 24 extends, which screw serves to clamp a spring clip 26, the angle member 20 and the adjusting arm 13 together. It will be seen that the slot 23 provides a range of adjustment between the arm 13 and the angle member 20 whereby the angular relationship between the bimetal 22 and the adjusting arm 13 may be varied. The spring clip 26 is bifurcated at its upper end to form a slot which is secured in an annular slot in the stud 14. Tightening of the screw 24 tensions the spring clip 26 to provide a side thrust on the adjusting arm 13 whereby enough friction is provided so that the arm 13 will remain in any of its adjusted positions.

A mercury switch 30 of conventional type is supported by the center of the spiral bimetal 22. The two lead wires 31 and 32 from the mercury switch 30 are secured to binding posts 33 and 34 extending through the base 10 and suitably insulated therefrom. It should be pointed out here that the only support for the mercury switch 30 is provided by the spiral bimetal 22, the angle member 20, and the adjusting arm 13. The mercury switch is not pivoted on the stud 14 shown in Figure 2.

Also mounted on the base 10 is a clockwork mechanism 38 which may be of any suitable type but is preferably of the type described in Patent 2,303,776 issued to Andrew G. Macmillan. Interdigitating from the clockwork mechanism 38 perpendicularly to the base 10 is a shaft 39 to which is secured

a cam 41, an indicia dial 42, and a setting knob 43. As shown in Figure 2 the clock mechanism is in its unwound position. The cover 11 has an opening 45 therein through which the indicia on the dial 42 may be seen. These indicia figures on the dial 42 represent hours. When the clock mechanism is in the unwound position the zero indicia appears in the opening 45 and as the setting knob 43 is turned in a clockwise direction to its limit of movement the eight hour indicia appears through the opening 45. As the clock mechanism is thus wound the cam 41 is also rotated to move a roller 48. The roller 48 is mounted on the upper end of a lever 50 which is pivoted on the stud 14 heretofore mentioned. A spring 52 is secured at its left hand end to a pin 53 mounted in the base 10 and at its right-hand end to the lever 50. The spring 52 serves to bias the roller 48 in a counter-clockwise direction against the cam 41.

The lever 50 is provided with a lower extension 56 which like the adjusting arm 13 extends between the base 10 and the indicia plate 16. This extension 56 lies beneath the adjusting arm 13 and is provided with a spring latch 58 which is secured thereto by means of a pair of rivets 59. The lower extremity of the latch 58 is provided with an upturned portion 61 which is adapted to engage the adjusting arm 13. The portion 61 is sloped so that it is higher at its right hand edge 62 than at its left hand edge 63. Therefore as the clock mechanism is wound and the cam 41 moves the lower extension 56 of the lever 50 to the left the latch 58 will be forced downwardly as it engages the adjusting arm 13. As the extension 56 is brought directly under the adjusting arm 13 the portion 61 of the latch 58 will spring upwardly so that its edge 62 will engage the left hand edge of the adjusting arm 13. Then as the clock mechanism turns the cam 41 in a counter-clockwise direction the lever 50 will also be moved in a counter-clockwise direction and the adjusting arm 13 will be similarly moved.

As pointed out above the present thermostat was designed particularly for controlling the temperature within tobacco drying barns. For such a purpose it has been found desirable to provide a thermostat in which the temperature can be manually adjusted from 80° F. to 100° F., the temperature raised through an eight hour period from 100° F. to 140° F., and then raised manually from 140° F. to 180° F. The function of the clock mechanism of the present thermostat is to automatically raise the temperature from 100° F. to 140° F. in an eight hour period. Obviously by providing a cam of the desired shape any desired rate of temperature increase throughout this eight hour period may be obtained. When it is desired to start the process the spring latch 58 may be depressed and the adjusting arm 13 moved to the extreme left as shown in Figure 2. An attendant manually positions the adjusting arm 13 between 80° and 100° at any desired rate. After the arm 13 has been adjusted for a temperature of 100°, the setting knob 43 is rotated in a clockwise direction until the cam 41 has reached the limit of its movement at which setting the latch 58 on the lower extension 56 of the lever 50 will engage the arm 13. The numeral 8 will then appear at the opening 45 indicating that eight hours remain before the temperature will be raised to 140°. As the clock mechanism runs down it rotates the cam 41 to gradually raise the temperature to 140°.

At this point it is desired to manually adjust the temperature setting of the thermostat to obtain higher temperatures. Obviously the adjusting arm 13 may be moved to the right beyond the position to which the clock mechanism has moved it. The thermostat may be in control of any suitable source of heat such as a fuel burner or steam valve.

The clock mechanism is provided with a slip friction drive so that it may be set in both directions by the setting knob 43. Thus the clock mechanism may be manually set towards the direction in which the thermostat calls for higher temperatures.

It will be seen from the foregoing description that a thermostat has been provided in which the temperature adjustment can be made both manually and automatically according to a timed program. It is to be understood that I am not to be limited to the particular thermostat described but only by the scope of the appended claims. It should be pointed out that certain of the features of novelty involved are equally applicable to other control devices such as humidity and pressure controllers.

I claim as my invention:

1. In a thermostat, in combination, a thermostatic element, control means operatively connected to said thermostatic element, manually positionable means for adjusting the temperature at which said thermostatic element actuates said control means, and time responsive means manually engageable and disengageable with said manually positionable means for moving said manually positionable means through a continuous timed program of adjustment.

2. In a control device, in combination, a condition responsive element, a control element operatively connected to said condition responsive element, manually positionable, selecting means for adjusting the value of the condition at which said control element will be actuated by said condition responsive element, a clockwork, a cam adapted to be rotated by said clockwork, a member positioned by said cam, and connecting means adapted to cause movement of said selecting means by said member in a single direction.

3. In a control device, in combination, a thermostatic element, a switch adapted to be actuated by said element, manually positionable selecting means for adjusting the temperature at which said switch will be actuated by said element, a clockwork, a member positioned by said clockwork, and interconnecting means for releasably attaching said selecting means and said member whereby said clockwork may position said selecting means to vary the control temperature of the device when said interconnecting means is effective.

4. In a control device, in combination, a thermostatic element, a switch adapted to be actuated by said element, selecting means for adjusting the temperature at which said switch will be actuated by said element, a clockwork, a member positioned by said clockwork, means for releasably attaching said selecting means to said member, and means for manually winding said clockwork and simultaneously causing engagement of said selecting means by said member.

5. In a thermostat, in combination, a thermostatic element, a control element operatively connected to said thermostatic element and adapted to be actuated thereby, selecting means to adjust the temperature at which said thermostatic element will actuate said control element, a clock-

work, a cam adapted to be rotated by said clock-work, a lever positioned by said cam, and latching means for operatively connecting said lever to said selecting means.

6. In a thermostat, in combination, a base, a thermostatic element mounted on said base, an electric switch adapted to be actuated by said thermostatic element, an adjusting member pivoted in said base adapted to vary the control temperature at which said thermostatic element actuates said switch, a cam, a clock mechanism mounted on said base and adapted to rotate said cam, a cam follower pivoted in said base, and means positioned by said cam follower for moving said adjusting member, said adjusting member being manually adjustable independently of said cam follower.

7. In a thermostat, in combination, a base, a first lever pivoted on said base, a bimetal element secured to said lever, a mercury switch mounted on said bimetal element, a second lever pivoted on said base, a cam for positioning said second lever about its pivot in said base, a clockwork mounted on said base for positioning said cam with respect to said base, and means for causing said first lever to move with said second lever whereby the control temperature of the thermostat will be varied as said clockwork adjusts said cam, said first lever being manually positionable independently of said second lever.

8. In a thermostat, in combination, a thermostatic element, control means operatively connected to said thermostatic element, manually positionable means for adjusting the temperature at which said thermostatic element actuates said control means, a spring driven clockwork having a winding knob, a cam rotatable with said winding knob, a lever adapted to be positioned by said cam, and a latch on said lever for engaging said manually positionable means when said clockwork is wound whereby said clockwork will be effective to vary the control point of the thermostat.

9. In a control device, in combination, a condition responsive element, control means operatively connected to said condition responsive element, a cover for said condition responsive means and said control means, manually positionable means extending outside of said cover for adjusting the value of the condition at which said condition responsive element actuates said control means, and time responsive means for continuously adjusting said manually positionable means during a predetermined continuous timed program.

10. In a thermostat, in combination, a thermostatic element, control means operatively connected to said thermostatic element, adjustable means for determining the temperature at which said temperature responsive means actuates said control means, said adjustable means being manually adjustable, time responsive means, and means to connect said time responsive means and said adjustable means when said adjustable means is within a predetermined range for continuously adjusting the temperature setting of said thermostat to a predetermined value which is independent of any previous temperature setting of said adjustable means within the predetermined range.

11. In a control device, in combination, a thermostatic element, a switch adapted to be actuated by said element, selecting means for adjusting the temperature at which said switch will be actuated by said element, a clockwork, a member positioned by said clockwork, means for releas-

ably attaching said selecting means to said member, and means for manually winding said clock-work for causing engagement of said selecting means by said member without moving said selecting means.

12. In a thermostat, in combination, a thermostatic element, control means actuated by said thermostatic element, a member for determining the temperature at which said thermostatic element actuates said control means, manually positionable means for positioning said member, and time responsive means for positioning said manually positionable means in such a manner as to continuously vary over a predetermined period of time the temperature value at which said thermostatic element will actuate said control means.

13. In a thermostat, in combination, a thermostatic element, a control element operatively connected to said thermostatic element and adapted to be actuated thereby, selecting means to adjust the temperature at which said thermostatic element will actuate said control element, time responsive means, a lever positioned by said time responsive means, and means for operatively connecting said lever and said selecting means.

14. In an automatic temperature control device of the character described, an adjustable thermostatic switch means, a pivoted control arm connected to said switch means and operable at will, for adjusting the switch means to change the active temperature-range thereof, a re-settable clock motor including a drive shaft, a cam on said shaft, a pivoted lever engaging said cam for pivotal displacement thereby, a releasable connector on said lever, adapted for operatively connecting said lever to said control arm, and means for turning said shaft to wind up the clock motor and coincidentally therewith, to rotate said cam to an initial operative position, and thereby to actuate said lever to an initial position for connection by said connector, with said control arm, said clock motor when wound, rotating said cam and thereby actuating said lever to cause pivotal displacement of said control arm in an automatic and continuous manner, whereby to cause continuous adjustment of said switch means to change the active temperature-range thereof.

15. In an automatic temperature control device of the character described, a pivoted member, a thermostatic switch means carried by said member, a pivoted control arm connected to said member and operable at will, to pivotally displace said member and switch means thereon, for changing the active temperature-responsive range of said thermostatic switch means, a lever pivoted coaxially with said control arm, a releasable connector on said lever, adapted for connecting the lever to said control arm, a re-settable clock motor including a drive shaft, a cam on said shaft engaging said pivoted lever, and means for turning said shaft to thereby wind up said clock motor and coincidentally therewith, to rotate said cam to an initial operative position, said cam in attaining such initial position, thereby displacing said lever to an initial position for connection by said connector, with said control arm, the subsequent rotation of said cam by said clock motor thereby effecting a pivotal displacement of said lever automatically and continuously at a predetermined rate and for a predetermined time period, and through said connector, a corresponding displacement of said control arm, to effect an automatic and continuous change in the active

temperature-responsive range of said thermostatic switch means.

16. A temperature control device of the character described, comprising co-axially pivoted levers, a thermostatic switch means carried by one of said levers and adjustable in response to pivotal movement of said lever, for varying the active temperature-range of the switch means, a time-operated cam engaging another of said levers for pivotal actuation thereof, and a releasable connector on one of the levers, adapted for connecting the levers together for concurrent pivotal movement in response to the operation of said cam.

17. A temperature control device of the character described, comprising a pivoted member, a thermostatic switch means carried by said member and being adjustable in response to pivotal movement of said member, for varying the active temperature-range of the switch means, coaxially pivoted levers, one of said levers being connected to said member and movable at will, to effect pivotal movement of the member, a time-operated cam engaging another of said levers for pivotal actuation thereof, and a releasable connector on one of the levers, adapted for connecting said levers together for concurrent pivotal movement in response to the operation of said cam.

18. A temperature control device of the character described, comprising a pivoted member, a

thermostatic switch means carried by said member and being adjustable by pivotal movement of the member, for varying the active temperature-range of the switch means, a pivoted lever connected to said member and manually movable at will, between predetermined limits, to effect a corresponding pivotal movement of said member, a time-operated cam, a second pivoted lever engaging said cam for pivotal actuation thereby, and means on one of said levers adapted for effecting a releasable connection of said levers for concurrent pivotal movement in response to the operation of said cam.

19. In a thermostat, in combination, a base, a thermostatic element mounted on said base, an electric switch adapted to be actuated by said thermostatic element, an adjusting member pivoted in said base adapted to vary the control temperature at which said thermostatic element actuates said switch, a cam, a clock mechanism mounted on said base and adapted to rotate said cam, a cam follower for continuously engaging said cam, and means positioned by said cam follower for moving said adjusting member, said cam and said cam follower cooperating in such a manner as to continuously vary the position of said means during the period of rotation of said cam by said clock mechanism, and said adjusting member being manually adjustable independently of said cam follower.

CARL G. KRONMILLER.
